UNITED STATES PATENT OFFICE.

JOHN H. FOY, OF PHILADELPHIA, PENNSYLVANIA.

CORNER-FORM FOR CONCRETE CONSTRUCTION.

1,129,658.

Specification of Letters Patent. Patented Feb. 23, 1915.

Application filed June 3, 1914. Serial No. 842,827.

To all whom it may concern:

Be it known that I, JOHN H. FOY, a citizen of the United States, residing in Philadelphia, Pennsylvania, have invented an Improved Corner-Form for Concrete Construction, of which the following is a specification.

My invention relates to forms employed in the molding or casting of concrete structures, more particularly walls, columns, girders, beams, and the like, and the object of my invention is to provide a metallic member for the corners of such forms, which member is so constructed as to provide a chamfered corner for the finished structure; said member having also portions for attachment to or reception of the side boards employed in making up the complete form. These and other features of my invention are more fully described hereinafter, reference being had to the accompanying drawings, in which:

Figure 1, is a perspective view of one type of my improved corner member for use with forms for concrete construction; Fig. 2, is a sectional plan view of the same; Fig. 3, is a similar view illustrating a modification within the scope of my invention; Fig. 4, is a perspective view of the structure shown in Fig. 3; Figs. 5, 6 and 7, are views illustrating other modifications within the scope of my invention, and Fig. 8, is a diagrammatic plan view showing the corner members employed with a column form. In the accompanying drawings, 1 represents one type of corner member for concrete forms constituting the subject of my invention; having a diagonal wall 2 to form the chamfered corner of the finished structure, and a plurality of walls 3, 4 and 5, which form, in the present instance, pockets 6 to receive boards 7 making up the balance of the walls of the necessary enclosure or form in which the concrete structure is cast or molded. The corner elements are of metal, bent or otherwise formed to the desired shape, and they are preferably made in continuous lengths; extending in most instances from end to end of the form. When set in place, the boards and corner members providing the form may be tied together by means of wire, rope, or other encircling devices, or held by suitable clamping devices common in constructions of this character.

In some instances, it may be desirable to

stay the walls of the corner forming devices, and for this purpose, ears or projections 8 may be bent up from the walls 4; such ears or projections overlapping each other, as shown in Figs. 3 and 4, and having registering apertures for the reception of locking pins 9.

The depth of pockets may be varied, and in Fig. 5, I have shown a construction 1^a in which the walls 3 are shortened; having sufficient surface, however, to engage the boards 7.

The use of the pockets may be omitted by nailing or otherwise fastening the corner members to the boards 7, and in Figs. 6 and 7, I have shown modified constructions 1^b and 1^c in which one of the side walls forming a pocket is omitted. In the member 1^b shown in Fig. 6, the walls 5 are omitted, and in the member 1^c shown in Fig. 7, the walls 2 are omitted.

Fig. 8, is a diagrammatic view showing the manner in which the corner members are employed with a column form.

The corner members may be made in any size desired, and while I have shown a straight or flat wall 2 to form a flat chamfer, it will be understood that this wall may be concave or convex, if desired to form convex or concave surfaces on the chamfered corner edges of the finished column or other structure.

If desired, the corner members of the type shown in Figs. 1, 3, 5 and 6, may be stiffened by filling the triangular space 10 between the walls 2 and 3 with a filler piece of wood or other suitable material.

While I have shown a corner member for use in forming structures having a rectangular contour, it will be understood that the pockets or attaching means for the boards may be disposed in positions other than a right angle with respect to each other and that the wall 2 may have a correspondingly modified angle with respect thereto.

While I preferably employ sheet metal to form the improved corner members constituting my invention, it will be understood that such members may be of metal cast, rolled, or otherwise formed into the desired shape or contour.

I claim:

1. A corner element for concrete column forms comprising a strip of metal having its edge portions shaped to receive the edges of boards and make up the complete form,

- said strip having an inner wall disposed between said boards and extending diagonally from the inner wall of one board to the inner wall of an adjacent board.
5. 2. A corner element for concrete forms comprising a member having board receiving pockets in its edges, said member having an inner wall which extends diagonally between said pockets and from the inner surface of one board to the corresponding surface of an adjacent board.
3. A corner element for concrete forms comprising a strip of sheet metal having board receiving pockets in its edges disposed at right angles to each other, said metal strip having a wall extending diagonally between said pockets from the inner surface of one board to the inner surface of an adjacent board.
10. 4. A corner element for concrete column forms comprising a strip of metal having its edge portions shaped to receive the edges of boards making up the complete form, said strip having an inner wall disposed between said boards and extending diagonally from the inner wall of one board to the inner wall of an adjacent board, and means for stiffening said strip of metal.
5. A corner element for concrete column forms comprising a strip of metal having its edge portions shaped to receive the edges of boards making up the complete form, said strip having an inner wall disposed between said boards and extending diagonally from the inner wall of one board to the inner wall of an adjacent board, and means for stiffening said strip of metal.
15. 30. 35. 40. 45.
- In testimony whereof, I have signed my name to this specification, in the presence of two subscribing witnesses.
- JOHN H. FOY.
